United States Patent Office

Des. 185,628
Patented July 7, 1959

185,628

FOOD PACK OR SIMILAR ARTICLE

John De Augustine, East Syracuse, N.Y.

Application November 25, 1958, Serial No. 53,531

Term of patent 14 years

(Cl. D58—13)

FIG. 1.

FIG. 2.

FIG. 3.

FIG. 5.

FIG. 6.

FIG. 7.

FIG. 8.

FIG. 9.

Fig. 1 is a top plan view of a food pack or similar article embodying my new design;

Fig. 2 is a view in side elevation;

Fig. 3 is a view in end elevation;

Fig. 4 is a perspective view thereof;

Fig. 5 is a perspective view with the pack in a partially open condition;

Fig. 6 is a bottom plan view thereof in fully open condition;

Fig. 7 is an end elevational view thereof in fully open position;

Fig. 8 is a side elevational view thereof in fully open position; and

Fig. 9 is a perspective view thereof from above in fully open position.

I claim:

The ornamental design for a food pack or similar article, substantially as shown.
